Gilman Joslin

United States Patent Office.

GILMAN JOSLIN, OF BOSTON, MASSACHUSETTS.

Letters Patent No. 79,129, dated June 23, 1868.

IMPROVEMENT IN ELEVATOR.

The Schedule referred to in these Letters Patent and making part of the same.

TO ALL WHOM IT MAY CONCERN:

Be it known that I, GILMAN JOSLIN, of Boston, in the county of Suffolk, and State of Massachusetts, have invented certain new and useful Improvements in Elevators; and I do hereby declare the following to be a full and exact description thereof, reference being had to the accompanying drawings, and to the letters of reference marked thereon:

To enable others skilled in the art to make and use my invention, I will proceed to describe its nature, construction, and use.

The nature of my invention consists—

First, in hanging a series of buckets or carriages upon two endless chains or bands, said chains or bands running upon sprocket-wheels, which are disconnected with each other, the whole being so arranged and constructed that the carriages pass or swing between the sprocket-wheels, and always maintain a vertical position.

Second, in enclosing the endless chain or band within grooves, that in case the chain or band breaks, it cannot fall, since it completely fills the channel in which it runs.

Third, in arranging a guide near the top of the elevator to assist in keeping the carriage vertical, while swinging between the upper sprocket-wheels, as it passes from the ascending to the descending well-room.

Fourth, in bevelling the bottom of the carriage so that it may, in combination with the partition between the ascending and descending well-room, assist in guiding itself into the descending well-room.

Fifth, in arranging, in that part of the floor that forms the edge of the ascending well-rooms, a narrow trap-door, which may open upward, in case, from carelessness or accident, any part of the person of the passenger extends outward beyond the well-room sufficiently far to come in contact with it, the said door.

Drawings.

Figure 1 shows, in part elevation and part section, my improved elevator.

Figure 2 shows in elevation the upper sprocket-wheels, their hangings, the chain-bands with the connecting-bar, and one of the buckets or carriages hung thereto.

Figure 3 shows a part of one of the sprocket-wheels and chain, and also in elevation and section the box or channel in which the chain or band runs.

The sprocket-wheels D D', fig. 2, are provided with teeth or sprockets, so that the links of the chain H may mesh accurately with them. The form of the teeth or of the links may be varied to suit circumstances, it only being essential that the links of the chain or corrugations of a rope, supposing a rope is used, shall agree perfectly with the teeth or corrugations of the "sprocket"-wheels.

The sprocket-wheels are suspended to the hangers by short pins R R', fig. 2, which extend inwardly from the hangers only to the inner surface of the sprocket-wheels, and not across from one wheel to another, so that the space between the wheels is open and free for the passage of the buckets.

The chains H H', fig. 2, are connected at intervals by rods, one of which, N, is shown in figs. 1 and 2. Upon each of these rods a carriage or bucket, O O' O'', is hung.

In fig. 1, one of the carriages, O, is represented as having just cleared the partition V, between the ascending well-room W and the descending well-room W', and as passing between the sprocket-wheels, while the chains H H', fig. 2, which carry it, are passing over the sprocket-wheels.

S, fig. 1, is a guide, which, bearing against the inclined upper end of the carriage, serves to keep the carriage in a vertical position in case it should be unevenly loaded.

The incline a' b', at the bottom of the carriage, bearing against the partition V, also serves to keep the carriage erect. The incline a b, on the bottom of the carriage, is to prevent the carriage, in its descent, from striking on the partition V when it begins to descend.

The chain or band H fits nicely in a groove, L, fig. 3, formed by the pieces K K. As this chain is always confined within a limited groove, it would not fall, in case it should break, as the sides of the groove would sustain it, and thus make it act as a support for the rod N.

By this arrangement, that is, confining the chain within a groove, I avoid the great danger attendant upon chain or rope elevators.

The pair of lower sprocket-wheels are not shown, but are identical in construction with the upper ones, and may revolve on short pins, similar to R R', fig. 2, or both sprocket-wheels may be hung on a single shaft, since the buckets or carriages hang entirely below the axis of the lower wheels, as they pass from one well-room to the other.

My elevator is actuated by the pinion A operating on the large gear C, or by any convenient actuating device.

X is a narrow trap-door on the verge of the ascending well-room, so arranged that, in case, from accident or carelessness, any part of the person of the passenger projects outward beyond the well-room sufficiently far to come in contact with the door, it will open upward, thus preventing injury to the passenger.

Having thus described my invention, what I claim as my invention, and desire to secure by Letters Patent of the United States, is—

1. The arrangement of the upper sprocket-wheels and independent journals, leaving the space between the two wheels open for the passage of the carriages, substantially as described, and for the purpose set forth.
2. The guide S, operating in combination with the carriage, substantially as described, and for the purpose set forth.
3. Bevelling the bottom of a chain-elevator carriage and arranging the top of the partition V, substantially as described, and for the purpose set forth.
4. The narrow trap-door X, arranged and working substantially as described, and for the purpose set forth.
5. The endless chain or band enclosed within guides, substantially as described, and for the purpose set forth.

GILMAN JOSLIN.
